UNITED STATES PATENT OFFICE

1,924,511

SAND BOX

Gustav E. Peterson, Astoria, Oreg.

Application October 3, 1932. Serial No. 636,050

4 Claims. (Cl. 272—1)

The present invention relates to a sandbox for children and has for its object to provide a structure which is simple, inexpensive to manufacture, strong and durable, thoroughly efficient and reliable and otherwise well adapted to the purpose for which it is designed.

Another very important object of the invention resides in the provision of benches associated with the sandbox and capable of being adjusted 10 toward and away from the sandbox.

With the above and numerous other objects in view as will appear as the description proceeds, the invention consists in certain novel features of construction, and in the combination and arrangement of parts as will be hereinafter more fully described and claimed.

In the drawings:

Figure 1 is a top plan view of a sandbox embodying the features of my invention.

Figure 2 is a longitudinal vertical section therethrough taken substantially on the line 2—2 of Figure 1.

Figure 3 is a vertical transverse section therethrough.

Figure 4 is a side elevation thereof.

Figure 5 is a perspective view of one of the supports, and

Figure 6 is a perspective view of one of the benches.

Referring to the drawings in detail it will be seen that the letter B denotes generally a rectangular box like structure consisting of longitudinal side walls 5 and transverse end walls 6. Bottom sections 7 are fixed to the bottom edges of the end walls 6 and to adjacent portions of the side walls and terminate in spaced relation to each other and at their inner ends have rising therefrom walls 8 terminating short of the upper edges of the walls 5 and a play platform 9 is mounted thereon. Angle members 10 are fixed to the corners of the box like structure and extend downwardly therebelow to provide legs.

Bench supports comprise horizontal members 11 fixed under the bottom sections 7 inwardly of the legs 10 and extending out beyond the side walls 5 having their outer ends supported by legs 12. The outer portions of the members 11 are slotted as indicated at 14. The benches include the elongated planks 15 having cleats 16 fixed thereto and formed with ribs 17 to slide in the slots 14 so that the benches may be adjusted toward and away from the box like structure.

It is thought that the construction, advantages 55 and utility of the device will now be quite ap-

parent to those skilled in this art without a more detailed description thereof.

The present embodiment of the invention has been described in considerable detail merely for the purposes of exemplification since in actual 60 practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I 70 claim as new is:

1. A sandbox of the class described including a box like structure formed from four walls, bottom sections fixed to the walls to terminate in spaced relation to each other, risers on the inner portion of the bottom sections, and a platform 75 across the risers.

2. A sandbox of the class described including a box like structure formed from four walls, bottom sections fixed to the walls to terminate in 80 spaced relation to each other, risers on the inner portion of the bottom sections, and a platform across the risers, and being disposed at a level lower than the level of the upper edges of the wall.

3. A sandbox of the class described including a box like structure formed from four walls, bottom sections fixed to the walls to terminate in spaced relation to each other, risers on the inner portion of the bottom sections, and a platform 90 across the risers, angular members fixed to the corners of the box like structure and depending downwardly therefrom to form legs.

4. A sandbox of the class described including a box like structure formed from four walls, bottom sections fixed to the walls to terminate in spaced relation to each other, risers on the inner portion of the bottom sections, and a platform across the risers, elongated members fixed under the bottom sections and extending beyond the side walls of the box like structure and being slotted, legs supporting the outer ends of the elongated members, planks, cleats on the planks having ribs slidably mounted in the slots.
